UNITED STATES PATENT OFFICE.

THOR H. LANGE, OF BRIDGEPORT, CONNECTICUT, ASSIGNOR TO WHITING MANUFACTURING COMPANY, OF NEW YORK, N. Y., A CORPORATION OF NEW YORK.

LAMP.

1,036,523.

Specification of Letters Patent. Patented Aug. 20, 1912.

Application filed May 15, 1912. Serial No. 697,396.

To all whom it may concern:

Be it known that I, THOR H. LANGE, a citizen of the United States, residing at Bridgeport, in the county of Fairfield and 5 State of Connecticut, have invented a certain new and useful Improvement in Lamps, of which the following is a specification.

The invention relates to lamps adapted to burn alcohol or hydrocarbons for heating 10 purposes, and is designed more especially for service with tea or coffee urns, chafing dishes and analogous utensils.

The object of the invention is to provide a lamp of this character which shall be simple and economical in construction, not liable 15 to derangement, and in which the flame may be easily controlled or regulated from various points adjacent to the lamp.

The invention consists in certain details 20 of construction by which the above objects are attained, to be hereinafter described.

The accompanying drawings form a part 25 of this specification and show an approved form of the invention.

Figure 1 is a side elevation of the improved lamp, showing its position relatively to a stand and kettle represented in dotted lines. The remaining figures are on a larger 30 scale and show the lamp alone. Fig. 2 is a plan view. Fig. 3 is an elevation of the side opposite to that shown in Fig. 1, and Fig. 35 4 is a vertical axial section taken on the line 4-4 in Fig. 3.

Similar letters of reference indicate the 40 same parts in all the figures.

A is the cylindrical body portion of the lamp, formed of thin metal and having an annular offset or shoulder A¹ by which it is supported in any suitable opening or socket 45 provided for the purpose. It has a neck A² terminating at the top in a narrow ring or collar A³ from which a bracket A⁴ projects laterally having a fixed vertical pin A⁵ serving as a pivot for a horizontally swinging cover B.

The cover is a plane circular disk of metal having a projection B¹ matching the contour of the bracket A⁴ and receiving the pin A⁵. The cover is slightly larger in diameter 50 than the collar A³ and in the closed position completely overlies the opening therein.

On the cover at about the center is riveted a vertical stud B² receiving a loose sleeve C to which is secured a horizontally-extending 55 rod C¹ terminating in a handle C², by which

the cover may be swung upon its pin A⁵ within the limits prescribed by an arm C³ on the projection B¹ arranged to strike the edge of the bracket A⁴ and serve as a stop in the closed position, and a lug A⁷ on the bracket serving as a stop in the fully open 60 position.

Any preferred form of wick may be employed; that shown consists of a perforated shell D received in the body A, having a filling D¹ of asbestos or the like, with a cover of wire cloth D² and provided with an arm D³ received in a notch a in the collar A³, by which it may be removed to permit the introduction of alcohol or other spirits 70 into the body portion A.

Upon the pin A⁵ is a head A⁶ of large area to resist vertical movement of the cover relatively to the body, and thus to permit the whole to be lifted and carried by the rod 75 C¹ without danger of derangement, and the loose connection of the rod to the stud B² permits the cover to be manipulated by the rod from any position in which the latter may be placed, as for example, in either of 80 the spaces between the standards indicated in dotted lines in Fig. 1 as supporting the kettle.

By moving the cover to vary the area of the exposed portion of the wick, the flame 85 is readily adjusted or extinguished, and, as above stated, the movement may be made with the rod at any angle relatively to the lamp.

The lamp is especially intended to be 90 made of silver for service with tea sets and the like, made of similar costly material, and it is essential that the amount of such material used in the lamp be as small as practicable and that the construction shall 95 require few parts, simply but efficiently joined and capable of withstanding the heat of the flame. The improved lamp attains these desired ends successfully.

I claim:

1. In a device of the character set forth, a lamp-body having an opening at the top, a cover pivotally connected to said body at one side of said opening and constructed to swing horizontally to open or close said opening, an operating rod loosely pivoted upon said cover and coacting means on said cover and lamp-body arranged to arrest the movement of said cover in the fully opened and closed positions of the latter. 100 105 110

2. In a device of the character set forth, a lamp-body having an opening at the top, a cover pivotally connected to said body at one side of said opening and constructed to swing horizontally to open or close said opening, an operating rod pivotally connected to said cover at or near the center thereof, an arm on said cover, and stops on said body arranged to be struck by said arm and arrest the movement of said cover in the

fully opened and closed positions of the latter.

In testimony that I claim the invention above set forth I affix my signature, in presence of two witnesses.

THOR H. LANGE.
